FIBER CLEANING CYLINDER

John Blewett, Dallas, Tex., assignor to The Murray Company, Dallas, Tex., a corporation of Texas

Application October 21, 1935, Serial No. 45,946

3 Claims. (Cl. 19—94)

This invention relates to new and useful improvements in fiber cleaning cylinders.

This invention has particularly to do with cylinders for use in fiber cleaning machines such 5 as cotton cleaners.

One object of the invention is to provide a cleaning cylinder for use in a machine employing a number of such cylinders for cleaning fibers such as cotton, and involving an improved structure whereby certain advantages of particular 10 importance are obtained.

An important object of the invention is to provide a cleaning cylinder preferably of the cruciform type, which has imperforate outer surfaces, 15 thereby avoiding accumulations of fiber and trash within the cylinder, as well as doing away with breaking or chopping of fibers, leaves and stems, and producing a desirable fan action; also providing continuous pockets or cradles for carrying the fibers over the screens and delivering 20 them to the next cylinder without interlocking.

A further object of the invention is to provide an improved cleaning cylinder having wings or vanes at its ends acting to cast out fibers and 25 trash, thereby being self-cleaning and reducing the fire hazard to a minimum.

It has been found that by the use of these cylinders, no additional boll breaker is required and the quantity of shale, leaf trash, motes and 30 dirt removed necessitates the use of a larger conveyor than is ordinarily used; also the slight fan action, rather than a drastic one, and the beating effect given to the cotton as it passes over the screen, are more efficient in cleaning the cotton as well as imparting a bloom and a creamy 35 white color, which increases the value of the fibrous material being cleaned.

A construction designed to carry out the invention will be hereinafter described, together 40 with other features of the invention.

The invention will be more readily understood from a reading of the following specification and by reference to the accompanying drawing, in 45 which an example of the invention is shown, and wherein:

Figure 1 is a longitudinal sectional view of a cotton cleaner equipped with cylinders constructed in accordance with the invention,

50 Figure 2 is an enlarged transverse sectional view of the cylinder,

Figure 3 is a perspective view of one end of the cylinder,

55 Figure 4 is an enlarged longitudinal sectional view of the same, and

Figure 5 is a partial perspective view of one of the cylinder sheets.

In the drawing the numeral 10 designates a shaft which extends axially through the body 11 of the cylinder and projects beyond the ends thereof to form bearing trunnions. The cylinder body includes cruciform end plates 12, preferably cast with an axial box 13 and radial wings 14 on its outer face.

Each plate is formed with a marginal flange 15 on its inner face set back slightly from its edges to receive the body sheets 16, the edges of which abut the end plates. These sheets are fastened on the flanges by bolts 17 and nuts 18. The cruciform shape of the end plates produces 15 four equally spaced arms 19 along which the wings 14 extend. The flange 15 is shaped at the outer end of each arm to support on end a flat longitudinal bar 20. Radial spikes or pins 21 have their inner ends extending through both the 20 bars and the sheets. The shank of each spike is provided with an annular shoulder which engages the outer face of the sheet. The inner end of each shank is then flattened, thus holding the bars and sheets together. The spikes are 25 otherwise of the usual construction.

As the body is shown with four offsets or projections due to the arms 19 of the end plates, it will be so described, but it is to be understood that the number of arms and projections may 30 vary. In order to provide a continuous covering for the body the sheets are longitudinally overlapped and also to make for economical manufacture, each sheet is a duplicate of the other sheets and four sheets complete the covering or 35 shell.

Each sheet includes an intermediate longitudinal crown strip A which is of such size and shape as to snugly fit on its correlated bar 20. Inclined apron panels B and C extend inwardly 40 from the crown strip, the panel B being the advance panel and C the trailing or following panel. By observing Figure 5 it will be seen that each sheet has a substantially V-shape conforming to the contour of the arms 19 of the end plates. 45 The panels C each have at their inner edges, a longitudinal flange D bent therefrom.

When the sheets are fastened in the flanges 15, the flanges D overlap the inner edge portions of the panels B as is clearly shown in Figures 2 50 and 3. By this arrangement the only seams or breaks in the covering of the body come at the bases of the trailing panels C, leaving the crown strips and advance panels B smooth and continuous. The flanges and the panels are fas- 55

tened together by bolts 23, some of which also pass through the flange 15. Bracing spiders (not shown) shaped like the end plates 12, may be mounted on the shaft within the body 11 to give 5 additional strength.

The sheets 16 provide a continuous covering for the body and permit the body to be made hollow to reduce its weight, yet obviates any 10 openings in the body in which cotton fibers and trash may collect and choke the cleaner. All edges which might cut the materials are eliminated. Owing to the inclinations of both the 15 panels B and C, the materials are readily cast from the pockets formed between the offsets and also a slight fan action is set up which creates sufficient draft which forces the light dust and foreign matter through the screens. If openings 20 were present in the cylinder covering not only would the cotton and trash collect therein, but there would be a tendency to create too strong a fan action. The continuous covering also tends to strengthen the cylinder and to brace it against twisting.

In Figure 1, I have shown a plurality of cylinders mounted in a cotton cleaning machine. The bodies 11 are disposed over concaved screens 24 concentric to the shafts 10. The wings 14 pass in close proximity to the sides of the machine and act to cast the cotton fibers and trash outwardly, thereby preventing accumulation around the shafts between the end plates 12 and the sides of the machine. This not only makes the cylinders self-cleaning at their ends, but reduces the fire hazard to a minimum. The continuous coverings, formed by the sheets 16 and the offset structure, act most efficiently in forcing the trash through the screens and in pitching the fibers from one cylinder to the next without choking or interlocking.

40 It is pointed out that the term cruciform as used herein is used generally, and it is not intended that the cylinder be limited to having four wings, as shown, as any desired number of wings may be provided on each cylinder.

45 In practice the inclination of the long panel B

described as the advance panel as always leading is of a flatter angle than the trailing short panel C. This produces more of an outward pressure against the screen on the cotton carrying side B of each offset, whereas the more nearly radial short side C is designed to give a large clearance and to turn the cotton over in the pocket between adjacent offsets.

What I claim and desire to secure by Letters Patent, is:

1. A fiber cleaning cylinder including, cruciform end plates having outwardly directed arms, a shaft extending axially through said plates, elongated sheets each including a crown strip and inclined advance and trailing panels secured 15 on the arms of said end plates, each sheet having a flange on its trailing panel overlapping the advance panel of the next sheet, whereby a continuous offset covering is provided, bars attached to the end plates and underlying the crown strips 20 of the sheets, and spikes extending through the bars and the crown strips of the sheets.

2. A fiber cleaning cylinder including, cruciform end plates having outwardly directed arms, a shaft extending axially through said plates, 25 elongated sheets each including a crown strip and inclined advance and trailing panels secured on the arms of said end plates, each sheet having a flange on its trailing panel overlapping the advance panel of the next sheet, whereby a continuous offset covering is provided, bars attached to the end plates and underlying the crown strips 30 of the sheets, spikes extending through the bars and the crown strips of the sheets, and fiber-displacing wings on the outer faces of the end 35 plates radiating from the shaft.

3. A fiber cleaning cylinder including, longitudinal outwardly directed offsets, spikes extending from the outer ends of the offsets, each offset having unequal angular sides with long side advancing and short side trailing, and fiber displacing wings disposed radially on the ends of the body.

JOHN BLEWETT. 45
